UNITED STATES PATENT OFFICE.

JAMES B. HAMMOND, OF CAMDEN, MAINE.

CARRIAGE MECHANISM FOR TYPE-WRITERS.

SPECIFICATION forming part of Letters Patent No. 783,432, dated February 28, 1905.

Application filed May 11, 1901. Serial No. 59,796.

To all whom it may concern:

Be it known that I, JAMES B. HAMMOND, a citizen of the United States, residing at Camden, Maine, and temporarily residing at New York, State of New York, have invented certain new and useful Improvements in Carriage Mechanism for Type-Writers, of which the following is a specification.

In an application for Letters Patent of the 10 United States filed by me of even date here-with I have described a type-writing machine adapted for universal work in printing occidental or oriental languages or in printing the Braille system for the blind.

15 My present improvement relates to the paper-carriage and its attendant devices as applied to a machine of this character and to other features not strictly confined in their use to this special form of machine.

20 In the accompanying drawings, Figure 1 is a sectional view of a type-writing machine with my improved carriage and the mechanism belonging thereto in place. Fig. 2 is a plan view of the escapement and driving means 25 for the carriage, parts being broken away and some parts omitted. Fig. 3 is a rear view of the carriage, the escapement, and driving mechanism, parts being broken away. Fig.

30 4 is a plan view of the carriage with parts broken away and parts omitted, this view showing also the relation between the carriage and the printing-hammer and shuttle. Fig. 5 is a plan view of the pointer and erasing-shield, showing its relation to the erasing- 35 plate of the carriage. Fig. 6 is a similar view showing the erasing-shield thrown back out of use. Fig. 7 represents a part of the means for holding cards or the like. Fig. 8 is a sectional view relating to the arrangement of the 40 pointer and shield. Fig. 9 is a plan view of the arrangement to effect variable spacing. Fig. 10 is a sectional view along the shaft of the escapement ratchet-wheel. Figs. 11, 11^a, and 11^b show the change-gearing mechanism 45 and back-spacer. Figs. 12 and 13 are details relating to the winding mechanism for the carriage-spring. Figs. 14, 15, and 16 are details relating to the paper-roller-controlling devices. Fig. 17 is a detail plan view of a por-

tion of the paper-roller and the paper-feed 50 mechanism associated therewith.

The paper-carriage in its general form and features is substantially the same as that well known in the Hammond type-writer, it having a paper-receptacle *a* and a pair of paper-feeding rolls *b* *c*, between which the paper passes as it is fed upwardly for the line-space, the printing being done, as in the ordinary machine, by a hammer *d*, a type-shuttle *e*, and an interposed ribbon. 55

The carriage is supported by the rollers *f* at the rear thereof, upon which the back rail *g* rests, said back rail being attached to the end frames *h* of the carriage, and at its front the carriage is provided with a bar or rock-shaft *i*, which rests upon a roller *j*, journaled in the center-piece frame *k* of the machine. The rock-shaft at its ends is journaled in the arms *m*, forming forward extensions from the rack-bar of the carriage. The purpose of this 60 rock-shaft will be described more fully hereinafter, it being mentioned at this point to make clear how the carriage is supported and allowed to have its traversing movement. 65

Carriage-driving mechanism.—The paper-carriage is driven from the main spring-drum *o* by a flexible connection *q*, of cord or other suitable material. The cord is attached at one end to the spring-drum and passes thence to and up between two guide-rollers *p*, journaled 70 in bearings *r*, extending from the frame of the machine. The cord is attached at its other end to a clip *s*, held on the back bar *n* of the carriage. This clip can be set at either one end or the other of the bar by means of a latch 75 *t*, pivoted to the clip and having fingers or latch-pins *u* adapted to engage openings *v*, arranged at or near each end of the back bar. In the position shown the pull on the cord from the spring-drum will propel the carriage 80 to print from left to right, as in ordinary English. By simply raising the latch-piece, pushing the clip to the other end of this rod, and setting the latch again the same pulling force will propel the carriage in the other 85 direction to print from right to left for the oriental languages or for printing the Braille system for the blind. The guide-rollers *p* are 90 95

arranged centrally of the stroke of the carriage, and the driving band or cord passes around either the one or the other of these, extending thence to the end of the carriage.

5 The clip is formed in two parts, attached by a clamp-screw to the back bar. With this carriage capable of being propelled in either direction by the motor I have provided means whereby the same escapement mechanism is used, this operating constantly in one direction. For this purpose I interpose between the usual escapement ratchet-wheel w and the carriage rack-bar n' a gear-wheel additional to that marked x , commonly used in the Hammond type-writer, and by throwing either one or the other of these gear-wheels into mesh with the carriage rack-bar while the other is out of gear therewith the step-by-step movement of the carriage may take place in either 15 direction, being controlled by the same escapement acting in the one direction.

The ordinary escapement gear-wheel is shown at x loose on the shaft y of the escapement ratchet-wheel w . In the present instance 25 this gear-wheel is adapted to be shifted along said shaft to be thrown into and out of connection with the carriage rack-bar n' , while, however, maintaining its driving connection with the escapement ratchet-wheel, which is 30 done by a spline or pin connection z , extending from a ratchet-wheel 1, loosely arranged on the escapement-shaft and adapted to impart movement to the escapement-shaft from the carriage-spring rack-bar and gear x through 35 a pawl 2, engaged by the teeth of the loose ratchet 1, which pawl is pivoted to a disk 3, fixed on the escapement-shaft. By this construction the pull of the carriage-spring exerted through its rack and the escapement- 40 gear x will place a tension on the escapement ratchet-wheel, tending to move it for its escapement action, and at the same time the carriage can be run back to start a new line, as 45 is well known in this type of machine, the loose ratchet-wheel slipping around under the pawl on the disk 3.

The escapement-gear x meshes constantly with another and smaller shifting gear-wheel 4, which also is adapted to engage and disengage the carriage rack-bar n' . When this 50 smaller gear-wheel 4, which I term the "change-gear," is thrown into mesh with the rack-bar and the escapement gear-wheel x is thrown out of connection with the rack-bar, the carriage may move step by step from 55 right to left, the escapement ratchet-wheel moving constantly in the one direction and the action of the parts controlled thereby not being affected in any way, whether the carriage moves on its printing stroke in one direction or the other.

The change gear-wheel 4 is supported loosely upon a pin 5, supported in the frame, and both this gear and the escapement gear-wheel 65 are provided with grooved bosses 6, receiving

pins 7 of a lever 8, which is pivoted to a bracket 9 of the machine, a finger-lever 11 being provided, connected to the lever and having a spring-pin 12, which by shifting the finger-lever may be made to engage either one of two holes 13 in the bracket to hold the lever in either position. In one position the escapement-gear x is in mesh with the rack-bar while the small gear 4 is out of mesh, while in the other position the conditions are 75 reversed; but in both positions the two gear-wheels maintain their engagement with each other. It will now be seen that by adjusting the driving-band to connect with either one end of the carriage or the other and by 80 making a corresponding change in the gear-train by which the carriage-rack is connected with the escapement the step-by-step action of the carriage may be effected in either direction. 85

The disengaging-sleeve 14, by which the carriage may be rendered free to move in either direction, operates in connection with the spring-pawl 2, as in the well-known Hammond construction. This sleeve is operated 90 by means like that shown in the commercial form of the Hammond type-writer and consisting, as indicated in Fig. 1, of a rod 15, extending lengthwise of the carriage and connected at its ends to finger-levers 16, pivoted 95 on the carriage-frame at each end. The disengaging-rod passes through a depression 17 in the yoke 18 of the disengaging-sleeve. This disengaging device is common to both adjustments of the machine, and no matter whether the machine is set to print from right to left or the reverse the disengaging device operates the same in either case, and thus the carriage may be freed from its escapement mechanism without regard to the direction of the printing stroke. The rod 15 is held by links 100 19, Fig. 1, connected thereto and to the carriage-frame. 105

Back-space mechanism.—I have provided back-space mechanism common to both adjustments of the machine, so that the operator can by depressing a key move the carriage step by step in a direction the reverse of that for printing the characters. This mechanism comprises a back-space gear-wheel 20, the 110 shaft 21 of which is supported in the frame, said gear-wheel meshing constantly with the escapement gear-wheel x in all positions of the latter, it being sufficiently wide for this purpose. This gear is combined with a ratchet-wheel 22, engaged by a spring-pawl 23, carried by a pawl-lever 24, pivoted on the shaft 21 and under tension of a spring 26, tending 115 to hold the pawl-lever in normal position. The pawl is held normally out of engagement 120 with the ratchet 22 by a pin on the pawl engaging a cam-piece 23^x, fixed to the frame so that the carriage may be returned freely to begin a new line. A screw 23^y, Fig. 2, limits 125 the forward movement of the spacing mech- 130

anism. The pawl-lever is connected by a link 27 with a finger-lever 28, which is pivoted to the base-frame at 29 and extends forward to the keyboard, at which point a finger-key is 5 provided, marked "Back space." Each depression of this key will cause the spring-pawl to turn the back-space gear-wheel 20, and this, through the escapement-gear α , will move the rack back one step from left to right, or if the 10 escapement-gear α is out of mesh with the rack-bar and the smaller or change gear 4 is in mesh with it the rack-bar will be moved one step from right to left, this being backward in relation to the direction of printing. 15 From this it will be clear that the same back-space mechanism is used for both adjustments of the machine, and no separate adjustment of the said mechanism is necessary. This is also 20 true of the disengaging mechanism above described for freeing the carriage, and it is likewise true of the spacing mechanism and the space-key, these operating in the ordinary way and without special adjustment.

For the use of the blind in printing the 25 Braille system I provide a pointer and an erasing-shield. The pointer 30 consists of an arm having a single point thereon, said arm being provided with a hub 31, adapted to fit on the end of the anvil post or spindle 32 above the 30 anvil 33, which supports the type-shuttle. It is held in position with the pointer extending toward the printing-point by an arm 34, extending from the said hub and having a portion reaching down along the side of the cross-arm 35 of the anvil, the lower end of said portion being provided with a spring or friction shoe 36, adapted to fit under the lower edge of the said cross-arm, and thus hold the device in place. To place the pointer-arm in 40 position, its hub is placed on the projecting end of the spindle, and then by giving it a turn the spring-shoe will swing under the edge of the anvil-arm, and thus the pointer-arm will be held in place and the arm 34 will limit 45 the movement of the pointer-arm and determine its exact position, and, for this purpose said arm is provided with an adjustable stop projection 37 or pin, which by coming against the arm of the anvil will act as a means of accurately setting the pointer-arm.

The erasing-shield consists of a plate 38, pivoted to the pointer-arm, which may be swung backward, so that it will overlie the erasing-plate 39 of the carriage, upon which 55 the paper will be pressed with the character to be erased exposed through the slot in said shield, so that the operator by erasing the character at the slot can make correction. The shield on its top side is slightly concaved to 60 present a thin portion adjacent to the slot. When not in use, the erasing-shield may be swung to the front out of the way and so as not to obstruct a view of the printing being done.

65 A scale 40 for the blind is provided by me,

having a series of projections of the Braille system. It is secured to the carriage, and it and the top or erasing plate of the carriage may be swung back from normal position to expose the hammer for adjustment or 70 the other parts. For this purpose the erasing-plate is pivotally supported by arms 41, which are pivotally connected at their rear ends to the carriage-frame. The Braille scale is carried by arms 42, which are pivoted at 42', so 75 that this scale may be thrown back out of the way when not in use.

The ordinary scale may be used instead of the Braille scale.

Means are provided for holding cards to be 80 printed, said means consisting of a series of fingers 42", reaching down from a rock-shaft 43, supported in bearings in standards 44, extending up at the ends of the carriage from the arms 41, pivoted at 95, to be swung back. 85 These fingers grip the cards between themselves and the front edge of the erasing-plate. The shaft has a forked arm 45 engaged by the end of a pivoted finger-lever 46, and by this the fingers may be forced against the front edge 90 of the erasing-plate, or by moving the finger-lever in the opposite direction the fingers can be moved away from the erasing-plate, or the fingers may be swung up altogether out of the way, in which latter case the forked arm 95 would leave the finger-lever. This card-holder or supplemental paper-holder is arranged, as will be seen, above the printing device and above the paper-rolls, so that it will act to hold a sheet of paper so as to depend therefrom to 100 the printing devices, and this means will hold the paper after it leaves the paper-rolls, so that a line may be printed close to the lower edge of the paper. The release-lever 16 for the carriage is made longer than heretofore and 105 is brought up opposite a thumb-rest 47 on the frame of the carriage, so that by the thumb and finger the release-lever may be operated. This release-lever and thumb-rest are duplicated at the right-hand end of the carriage, so 110 that the carriage may be released by either hand.

Line-space feed—The line-space feed consists of a lever 48, which operates the paper-roll on its forward stroke instead of by its return stroke. This lever is pivoted to a lug 49 on the carriage-frame, and its inner end engages loosely a forked arm 50, pivoted to the end of the arm 51 in which the roll is journaled, said arm being pivoted at its lower end 120 to the back bar of the carriage, forming part of the frame thereof. A pin 52 on the pawl-carrying arm 53, which arm is pivoted on the axis of the roller, engages this forked arm. The pawl 54 is carried by this pawl-arm and 125 engages a ratchet 55 on the paper-roller 56. The movement of the pawl is limited by a pin 57, carried by an adjustable clip 58, which has a spring-pin 59 adapted to fit any one of a series of holes 60 in the bracket 61, of segmen- 130

tal form. The arrangement of the parts is such that the inward movement of the finger-lever will rotate the paper-roll, the movement being limited by the stop-pin as desired. 5 The pawl is held normally free from the ratchet by a pin 62 on the arm 51 engaging the tail of the pawl when the pawl is in normal position. It will be seen from this construction that the stop for the pawl is arranged 10 to contact therewith directly, and it is carried by the same arm which supports the paper-roll, always bearing the same relation to the pawl in all positions of the roll. The roll-carrying arm is under tension of a spring at 15 51', pressing the same toward the other roll. The segment for the adjustment of the stop is arranged to have an opening between itself and the supporting-arm, through which opening the pin 52 extends. The roll is held against 20 too free rotation by a detent 63 engaging a ratchet 64 at the opposite end of the paper-roll from the driving-ratchet. This detent may be thrown out of engagement with the ratchet, and the roller will then be entirely 25 free to rotate. For this purpose the detent is controlled by an eccentric or cam 65, journaled in a block 66, fixed to the back bar of the carriage, to which block also the detent is fixed, said eccentric being in turn operated by finger-lever 67, which projects to the rear through a 30 slot 68 in the detent itself. The detent is formed in one piece with a friction arm or finger 69, which is adapted to bear on a plain rim 70 on the paper-roll, and thus when the 35 detent is withdrawn from the teeth of the ratchet the friction-finger will hold the roll under frictional restraint. This friction-finger consists of an extension of the sheet-metal arm which forms the detent, said arm having 40 a portion 71 partially encircling the back bar of the carriage. By pivoting the arms carrying the paper-roll at their lower ends the upper part of the carriage is left free for the location of the printing mechanism or other 45 parts.

Variable-space mechanism.—I have provided means for obtaining variable spacing, so that in printing the "m" or "w," for instance, a large space may be provided and for printing the "l," for instance, a smaller space may 50 be produced. For this purpose I provide a sliding connection between the carriage and the rack, consisting of a screw 72 passing through an elongated opening 73 in the rack 55 into the carriage-frame, so that the paper-carriage may have longitudinal adjustment in relation to the rack. An arm 74 extends toward the front of the machine from each end of the carriage-frame, and this is formed as a 60 nut at its forward end to receive a screw or worm 75, carried upon the rock-shaft *i*, the ends of which are journaled in the arms *m*, rigidly attached to and extending forwardly 65 from the ends of the rack-bar. There is a finger-button 76 on the projecting ends of this

shaft, adapted to be held in any position to which it, with the shaft, may be turned by the spring-pawl 77 engaging one of a series of notches 78 in the button. This mechanism is duplicated at each end of the machine. The 70 shaft carrying the worms rests upon the roller before described, journaled on the centerpiece frame. By this construction the shaft may move longitudinally with the carriage and may be rotated at any time to move the 75 paper-holder in relation to the rack in either direction. In printing the "m," for instance, supposing the carriage to be moving from right to left, the operator by simply turning the button at either end of the machine can 80 adjust the paper-holder backward or to the right in relation to the rack, or in printing the "l" an adjustment in the opposite direction may likewise be effected.

The carriage-spring is wound by any suitable key, such as shown at 79, in the ordinary manner. The shaft of the spring-drum is provided with a pinion 80, which meshes with a gear-wheel 81, fixed to a shaft 82, journaled in the framework. This shaft carries a pinion 83, meshing with teeth 84, formed on a bar 85, which is arranged to slide in bearings 86, longitudinally of the machine, and is connected with the hammer-spring 87. This spring is connected at its other end with the 90 hammer-returning lever 88, well known in the Hammond machine. By this mechanism the hammer-spring will be adjusted simultaneously with the adjustment of the carriage-spring. In order to limit the adjustment of 95 the carriage-spring either way—that is, to increase or diminish its strength—I provide a stop device which includes a stop-arm 89, loosely arranged on the shaft 82 and within the recessed face of the gear-wheel 81. This 100 loose stop-arm has its end extending into the range of a stop-pin 90, fixed to the frame, and it is adapted to be moved by a stud or studs 91, projecting from the face of the gear-wheel 81 to engage the edge of the loose arm. As 105 the gear-wheel turns, the stud will carry the loose arm around with it until the arm strikes the stop-pin, which will thus limit the movement of the winding mechanism in that direction.

Fig. 13 shows the position of the parts with the movement of the winding mechanism arrested in one direction. If now it is desired to adjust the mechanism in the other direction, the adjusting action can continue till the stud 110 has been carried for nearly a full revolution of the gear-wheel before the stud will strike the other side of the loose stop-arm to carry the same along with it, and this arm will then have to make nearly a full revolution before 115 its opposite edge strikes the stop-pin to finally arrest the movement. By this stop mechanism a wide range of adjustment is possible.

In order to hold the erasing-shield, with its attached devices, up, I provide a depending ex- 120

tension 92, having a curved edge struck from the pivotal point of the arm 41, said curved edge having a series of notches 93 to be engaged by a spring-catch 94 to hold the said 5 erasing-plate in an elevated position. By this means the plate may be held up for as long a time as may be desired by the operator. The piece 47 on the carriage is provided with two surfaces, so that it may be used in connection 10 with the lever 48 and the releasing-lever 16. These surfaces are marked 47 and 47'. The base-frame of the type-writer is pivotally supported at 93^x to a suitable base, and by this arrangement the whole machine may be raised 15 and tipped back, so that access may be had to the parts beneath.

In order to allow sufficient movement of the carriage, the ribbon-spool shafts are not carried down to near the bottom of the machine, 20 as in my former machines. Instead these shafts extend but a short way below the spools and are driven by the ordinary mechanism comprising the shaft 96 and ratchet 97, which in the present arrangement are located at or 25 near the upper part of the machine.

I claim as my invention—

1. In combination with a reversible carriage with means for giving it a step-by-step action for printing a single escapement mechanism which is common to both spacing movements of the carriage, substantially as described.

2. In combination, the carriage with means for driving it in either direction and an escapement mechanism operating constantly in one direction, with connections between said escapement and the carriage, substantially as described.

3. In combination with a carriage, means 40 for giving it a step-by-step spacing movement in either direction during printing, a single escapement mechanism common to both spacing movements of the carriage and a change-gear connection between said escapement and the carriage, substantially as described.

4. In combination, the carriage, a motor with an adjustable connection between it and the carriage whereby the carriage may be impelled in either direction, an escapement and 50 an adjustable connection between the same and the carriage, substantially as described.

5. In combination with a carriage, means for driving it step by step in either direction for printing and release means for the carriage whereby it may be rendered free to move in either direction irrespective of the direction in which it is impelled, substantially as described.

6. In combination with a carriage, means 60 for driving it step by step in either direction for printing and release means common to both movements of the carriage, substantially as described.

7. In combination with a carriage, means 65 for driving it step by step in either direction

for printing, and a back-space mechanism common to both movements of the carriage, said back-space mechanism operating through a part of the said driving means, substantially as described.

8. In combination with a carriage, change-gearing in connection with the rack of said carriage consisting of two gears constantly in mesh with each other and arranged to alternately engage the said rack, substantially as 75 described.

9. In combination with a carriage, change-gearing in connection with the rack of said carriage, consisting of two gears constantly in mesh with each other and arranged to alternately engage the said rack, and a back-space mechanism in connection with the said change-gearing, substantially as described.

10. In combination with a carriage, means 85 for driving it step by step in either direction for printing including change-gearing, and back-space mechanism common to both movements of the carriage, said back-space mechanism operating through the change-gearing, substantially as described.

11. In combination with the carriage, a spring-drum and a flexible connection between the same and the carriage, said connection being adjustable from one end of the carriage to the other, substantially as described.

12. In combination with the spring-drum, the guide-rolls arranged substantially centrally of the stroke of the carriage and a flexible connection extending from the spring-drum past the guide and adapted to be attached 100 at either end of the carriage, substantially as described.

13. In combination, the spring-drum, a pair of guide-rollers arranged on the frame about centrally of the stroke of the carriage and a 105 flexible connection between the spring-drum and carriage passing between said guide-rollers and adapted to be attached at either end of the carriage, substantially as described.

14. In combination, the spring-drum, the 110 carriage having the bar extending longitudinally thereof, the clip adjustable from end to end of the bar with the latch for holding it in place and a flexible connection between said clip and spring-drum, substantially as described.

15. In combination with a type-writer carriage having a rack-bar, an escapement-gear meshing with the rack-bar, an escapement mechanism, a pawl-and-ratchet device between 120 said escapement-gear and escapement mechanism, said gear having a splined connection with the ratchet, means for shifting the escapement-gear into and out of engagement with the rack and a second gear in connection 125 with the escapement-gear operating in a reverse direction to the escapement-gear, substantially as described.

16. In combination with a type-writer carriage, reversible driving means for operating 130

- it step by step in either direction and a release-lever for the carriage at each end thereof with connections controlled thereby, substantially as described.
- 5 17. In combination with a type-writer carriage, a release-lever and a thumb-piece on the carriage arranged adjacent to the release-piece, substantially as described.
- 10 18. In combination with a carriage and its rack, a rod extending parallel with the carriage and adjacent to the keyboard, means for supporting said rod intermediate of its length and means at the end of said rod for adjusting the carriage and rack, substantially as described.
- 15
19. In combination with a carriage and rack having an adjustable connection between them, a shaft arranged at the front of the machine adjacent to the keyboard, means carried by said shaft for adjusting the relation between the rack and carriage, and connections between the said shaft and the carriage and rack respectively, substantially as described. 20

In testimony whereof I affix my signature in presence of two witnesses.

JAS. B. HAMMOND.
